COMBINED CAN TAP AND BOTTLE OPENER

Herbert D. Lane, 23 E. 14th, San Angelo, Tex. 76901

Filed Aug. 23, 1972, Ser. No. 283,239

Term of patent 14 years

Int. Cl. D7—06

U.S. Cl. D8—40

FIG. 1

FIG. 3

FIG. 4

FIG. 2

FIG. 5

FIG. 6

FIG. 1 is a perspective view of a combined can tap and bottle opener showing my new design;

FIG. 2 is a side elevational view of FIG. 1, the side opposite being a mirror image;

FIG. 3 is a top view of FIG. 2;

FIG. 4 is a left end elevational view of FIG. 2;

FIG. 5 is a right end elevational view of FIG. 2; and,

FIG. 6 is a bottom view of FIG. 2.

I claim:

The ornamental design for a combined can tap and bottle opener, substantially as shown and described.
